ATTORNEYS

UNITED STATES PATENT OFFICE.

CLARENCE GIFFORD AUSTIN, OF WOODSTOCK, ILLINOIS, ASSIGNOR OF ONE-HALF TO
BENJAMIN W. LANCE, OF GENEVA, ILLINOIS.

TOY GAS-FILLING PUMP.

Application filed July 11, 1925. Serial No. 43,082.

To all whom it may concern:

Be it known that I, CLARENCE G. AUSTIN, a citizen of the United States, and resident of Woodstock, in the county of McHenry 5 and State of Illinois, have invented a new and useful Improvement in Toy Gas-Filling Pumps, of which the following is a full, clear, and exact description.

My invention relates to improvements in 10 toy gas filling pumps, and it consists in the combinations, constructions, and arrangements herein described and claimed.

An object of my invention is to provide 15 a toy gas filling pump which in operation has the same appearances as the full size operative gas filling pumps used at automobile service stations.

A further object of my invention is to 20 provide a toy gas filling pump of the character described which employs liquid to represent liquid fuel and in which the liquid is so confined as to prevent its spilling upon the floor or other supporting surface upon which the toy is placed if for some reason 25 the toy is overturned.

A further object of my invention is to 30 provide a toy gas filling pump of the character described in which particularly novel structure is employed for pumping the fluid from the lower or concealed compartment, representing the underground tank in the full size operative embodiment of the gas filling pump, into an upper or visible compartment and from thence back to the concealed compartment, which latter step represents the movement of fluid through a 35 miniature hose into the fuel tank of a toy vehicle.

A further object of my invention is to 40 provide a toy gas filling pump of the character described which is durable in construction, simple in operation and thoroughly practical for the purpose intended.

Other objects and advantages will appear 45 in the following specification, and the novel features of the invention will be particularly pointed out in the appended claims.

My invention is illustrated in the accompanying drawings, forming part of this application, in which—

Figure 1 is a front elevation of an embodiment of my invention,

Figure 2 is a sectional view of the mechanism illustrated in Figure 1,

Figure 3 is a sectional view on the line 55 3—3 of Figure 1, and

Figure 4 is a perspective view of a part of the mechanism illustrated in Figure 3.

In carrying out my invention I make use of a base member 1 having a cylindrical 60 metal body member 2 mounted vertically thereon. The body member 2 has a reduced cylindrical member 3 mounted coaxially thereupon at the upper end, which member 3 supports a vertically extending 65 guard member 4. The guard member 4 has a top plate 5 upon which a metal name plate 6 is disposed and painted to simulate the illuminated name plate ordinarily disposed at the top of the gas filling pumps in 70 commercial use.

A reservoir 7 is concealed within the body member 2 and consists in a glass bottle similar to the bottles used for holding ink. This bottle 7 has a stopper 8 therein and 75 is held against movement with respect to the body member 2 by a metal partition wall 9 which bears against the top of the stopper 8, and which is secured to the side walls 80 of the body member 2.

The stopper 8 has three metal tubes 10, 11 and 12 projected therethrough. The tube 11 has its lower end disposed adjacent to the bottom wall of the reservoir 7 and has a ball valve 13 at its upper end which is 85 projected above the top of the stopper 8. The tube 10 has its lowermost end just below the bottom wall of the stopper and its upper end in a plane common with the ball valve 13. The tube 12 has its lower end in 90 common with the lower end of the tube 10 and its upper end projected through a stopper 14 disposed in the neck of an elongated glass bottle 15 which just fills the interior 95 of the guard member 4 and has the appearance of the visible reservoir employed in the full size operative gas filling station pump.

The upper end of the tube 12 is disposed adjacent to the upper end of the bottle 15. The bottle 15 is held against displacement 100 from the guard 4 by a partition wall 15 secured to the inner wall of the member 3, and which engages with the stopper 14.

Relatively short metal tubes 17 and 18 are projected through the stopper 14 and 105 each extends downwardly below the lower surface of the stopper 14 for approximately three-eighths of an inch, and have their up-

per ends slightly above the level of the upper surface of the stopper. The tube 18 has a ball valve 19 at the top thereof similar to the ball valve 13.

5 Soft rubber tubes 20 and 21 are employed for connecting the tubes 10 and 11 to the tubes 17 and 18 respectively, (see Figure 2).

10 A spring 22 is secured at its lower end to the partition wall 9 and has a portion thereof parallel with the axis of the rubber tube 21. A crank 23 having a shaft 24 is rotatably mounted on the body member 2 so that the shaft portion 24 extends across the interior of the body member adjacent to the 15 outer surface of the spring 22, while the crank portion 23 is disposed exteriorly of the body member.

15 The shaft 24 of the crank has a flattened portion 25 (see Figure 4) which causes the 20 spring 22 to oscillate laterally as the crank is turned, alternately squeezing and releasing the tube 21. This movement of the tube 21 causes water to be pumped from the reservoir up into the bottle 15.

25 A metal plate 26 having bearing members 27 is provided with a substantially horizontal portion 28 which is disposed between the tubes 20 and 21. The shaft 24 is projected through the bearing members 27, thus positively insuring the alternate squeezing and 30 releasing of the tube 21 as the crank is turned.

35 A second spring 29 is secured to the partition wall 9 at its lower end and has a portion 30 bent in the form of a V which is adapted for engagement with the tube 20 to shut off the return flow of fluid from the bottle 15 to the reservoir 7, as when a 40 screw 31 having a handle portion 32 is moved into engagement with the portion 30 of the spring 29. This screw 31 is rotatably mounted in threaded lugs 33 which depend from the plate 26. A miniature hose 34 of rubber tubing or solid rubber is secured at 45 35 to the body member 2 and has at its outermost end a miniature spout member 36. No liquid is intended to pass through the hose 34, nor the spout 36 which merely serve as toy members to simulate their counterparts found in the standard full size gas filling pump.

50 From the foregoing description of the various parts of the device, the operation thereof may be readily understood. Normally all of the fluid or liquid in the device is within the reservoir 7, there being also liquid between the ball valve 13 and the ball valve 19. When the crank 23 is turned, the portion 25 will alternately engage and 55 disengage the spring 22 so as to cause the

tube 21 to be first squeezed and then released. This causes the fluid within the tube 21 to be forced upwardly through the valve 19 into the bottle 15, or when the tube is released will cause fluid from the reservoir 65 7 to be drawn upwardly into the tube. This operation is repeated by turning the crank 23 until the bottle 15 has sufficient fluid therein to rise to a level indicated by a zero 70 mark which forms one of a plurality of gauge marks 35 inscribed upon the outer wall of the bottle 15. The top of the tube 12 is in a plane common with the zero mark on the bottle and any additional fluid pumped into the bottle will flow back 75 through the tube 12 into the reservoir 7.

The tube 12 also serves as an air vent to permit air to be admitted above the level of fluid in the reservoir 7 as the fluid is pumped therefrom.

80 The spout 36 is then placed over the fuel tank of a toy motor vehicle or the like and the screw 31 released from engagement with the spring 29. The fluid is then free to flow through the tube 20 back into the reservoir 7, giving the appearance of the flow of fluid through the miniature hose 34 into the tank of the toy vehicle.

I claim:

1. A toy gas filling station of the character described comprising a concealed reservoir for containing fluid, a visible reservoir of transparent material, means for pumping the fluid from the concealed reservoir into the visible reservoir, manual means for controlling the flow of fluid from said visible reservoir back into the concealed reservoir, said last named means consisting of a flexible tube having its opposite ends communicating with the interior of said concealed reservoir and with the interior of the visible reservoir, a spring having a portion thereof adjacent to the tube, and a manually actuated screw for moving said resilient member into engagement with the tube to constrict the tube.

100 2. In a toy gas filling pump of the character described, a concealed reservoir, a visible reservoir, and means for pumping fluid from the concealed reservoir to the visible reservoir comprising a tube projected into the concealed reservoir and a tube projected into the visible reservoir, a ball valve at the top of each of said tubes, said visible reservoir being disposed above the concealed reservoir, a flexible tube connecting the adjacent ends of said tubes, and manually actuated means for constricting and releasing said flexible tube alternately.

CLARENCE GIFFORD AUSTIN,
